OFFSHORE DRILLING PLATFORM

Kenneth C. Howard, Fort Worth, Tex., assignor
to Richardson & Bass, Fort Worth, Tex., a corporation of Texas

Application July 8, 1948, Serial No. 37,599

5 Claims. (Cl. 61—46)

1

This invention relates to oil well drilling apparatus, and has reference to an off-shore drilling platform.

An object of the invention is to provide a construction whereby off-shore drilling platforms may be imbedded and secured in subaqueous sand, silt, or the like, so as to provide a firm foundation for the said platform.

Another object of the invention is to provide a construction for off-shore drilling platforms which may be made into relatively large sections and floated by their own buoyancy to the desired drilling location.

A further object of the invention is to provide floatable sections for an off-shore drilling platform which may be vertically placed, prior to imbedding the same in the subaqueous soil, without using heavy equipment such as cranes or other heavy machines.

Another object of the invention is to provide an off-shore drilling platform which, when assembled, is unusually strong, and one which is capable of resisting wave action and strong water currents frequently encountered in off-shore drilling.

A further object of the invention is to provide an off-shore drilling platform which may be easily salvaged when required.

A particular object of the invention is to provide a floatable large section or subassembly for an off-shore drilling platform having floats at the lower end thereof, whereby water or air may be introduced into the same for either sinking or raising the same.

A further object of the invention is to provide floats or pontoons at the lower ends of sections of off-shore drilling platforms, and which pontoons or floats may be imbedded in the subaqueous soil so as to provide sufficient soil engaging area for supporting the drilling platform when the latter is imbedded at the drilling location. In accordance with the present invention this is accomplished by making each pontoon relatively long in comparison with its cross sectional diameter, so that the pontoons may be sunk deeply into the soil or silt, thus enabling them to resist the wave or current action, which action if applied to relatively short but broad based pontoons would soon erode the soil from beneath the pontoons, rendering them ineffective as bases or foundations for the supporting columns, and permitting shifting of the platform carried by the columns. The area of contact with the silt may be greatly increased by providing the floats with longitudinally extending fins or the like.

These and other objects of the invention will become apparent from the following description of the accompanying drawings, wherein:

Figure 1 is an elevational view of a drilling platform embodying the features of the present

2

invention, and showing the same imbedded in the subaqueous soil of an off-shore drilling location.

Figure 2 is an enlarged elevational and sectional view of one of the pontoons or floats secured to the lower end of a tubular support.

Figure 3 is a side elevational view of one of the sections illustrated in Figure 1 and showing the same having its end supported on a barge for floating the said section to the drilling location.

Figure 4 is a transverse sectional view of one of the pontoons or floats illustrated in Figure 1.

Figure 5 is a broken elevational view of a modified form of pontoon, first illustrated in Figure 1, but showing an annular nozzle means in addition thereto for washing soil upwardly around the said pontoon when the latter is being implaced in the subterranean soil.

Figure 6 is a perspective view of an arrangement for securing the sections of the drilling platform together at their upper ends.

The form of the invention illustrated in Figure 1 includes units or sections 1 including a multirle of tubular supports or columns 2. The broad side of a section 1 is illustrated in Figure 1, whereas the width of a section is illustrated in Figure 2. The illustrated relation of width to side is merely exemplary and not to be construed as a limitation. The tubular supports 2 are arranged in spaced parallel relation with respect to each other and are secured by braces 3 which are welded in place. The lower end of each tubular support 2 is encased by a closed longitudinal tubular float or pontoon 4 having round ends, as shown in detail in Figure 2. Within the length of each tubular support 2 there is a water washing pipe 5 which opens outwardly of the bottom center of the elongated float 4. As will be seen, the purpose of the water pipe 5 is to wash away the subaqueous soil for sinking the pontoon into place. Another small pipe or air line 6 is provided through the length of each tubular support 2 and has its lower end disposed through the said support and into the upper end of the float 4. Similarly, another small pipe or ballast line 7 extends downwardly through the tubular support 2 to where it opens into the lower end of the pontoon or float 4.

Each assembled section may be floated to the drilling location by securing the upper end of the same to a barge 9 or other vessel. When the barge 9 is above the desired location, the air in the floats 4 is evacuated through the small pipe 6, and water is introduced into the said floats by means of the water supply pipes 7. The floats then sink to the surface of the subaqueous soil and the section 1 assumes a vertical position since the upper end of the section is supported by the barge 9. It is to be understood that the depth of the water at the drilling location is known, and that the height or length of each section 1 is made accordingly, and so that

the upper end of the said section will project above the surface of the water. After the section 1 has assumed the described vertical position, water is forced under pressure downwardly through the wash line 5 where it disturbs and washes away the silt or soil 10 beneath the floats 4. By reason of the weight of the assembly 1, and the described washing action, the floats 4 sink into the soil or silt 10. It is preferred that the floats 4 be completely submerged in the soil or silt 10 so as to resist the wave and current action on the supports 2.

Another section or assembly 1 is then floated to location and lowered adjacent to the previously installed section 1 in the manner previously described. After a sufficient number of sections have been thus placed, the upper ends of each section are secured by suitable means such as the illustrated diagonal cross-ties 11 which are secured to the ends of the upper horizontal plates 8 by means of bolts 12. Each cross-tie 11 may be secured one to the other where they cross by other bolts 13. When the assembly of sections 1 is completed, a suitable platform 14 is secured on the upper ends thereof and a well derrick 15, indicated by dotted lines in Figure 1 is positioned on the said platform. The well casing 16 beneath the derrick 15 is also indicated by means of dotted lines.

As shown in Figures 1 through 4, the described floats 4 may be provided with radially extending longitudinal fins 17 for increasing the area in contact with the silt 10 after the latter has settled around the said floats.

The entire described drilling platform may be completely salvaged by removing the platform 14, the cross-ties 11, and by lifting the separate sections 1 by means of evacuating water from the floats 4 and introducing air therein to again make the sections floatable. In many cases it may be desirable to flush the silt at the lower end of each float 4 by means of the water supply line 5, and thus disturb the silt and release the said float. The sections are then floated to land by means of the barges 9 in the manner previously described.

The float 4 illustrated in Figure 5 is similar to the ones previously described but differs in that a convex air chamber 18 is positioned over the lower end of the said float, and which chamber is provided with an inwardly directed flange 19 around its periphery, and which flange is perpendicular to the curved lower surface of the said float. A series of upwardly and outwardly directed orifices 20 are formed in the flange 19 and communicate with an opening 21 in the wash pipe 5. The last described arrangement of orifices 20 is in addition to the washing action at the lower end of the said wash pipe. The last described arrangement is for the purpose of augmenting the washing action and moving the silt upwardly along the surface of the float 4.

The described form of the invention is not restrictive, but may be made in many ways within the scope of the appended claims.

What is claimed is:

1. A supporting unit for an off-shore drilling platform comprising a rigid tubular support and a closed streamlined float connected to the tubular support at one end thereof, said unit being adapted to be floated to a place of assembly in a horizontal position, the float lowered beneath the surface of the water and embedded in the subaqueous surface while a portion of the rigid tubular support projects upwardly beyond the 75

surface of the water to permit attachment of the drilling platform, said float being of tubular form rounded at its lower end and surrounding the lower portion of the support, jetting means comprising a pipe extending downwardly through the tubular support and opening through the bottom of the float for supplying jetting fluid beneath the float for removing mud or silt to facilitate embedding and removing the float, means for selectively supplying and removing air to and from the interior of the float comprising a second pipe separate from the jetting pipe and extending downwardly through the tubular support and communicating with the upper portion of the interior of the float, and means comprising a third pipe extending through the tubular support and communicating with the interior of the float at the lower portion thereof for selectively supplying to and removing from the float ballast fluid, permitting the float to settle to the bottom or to be floated to the surface as desired.

2. A supporting unit as set forth in claim 1, wherein a convex chamber is positioned beneath the lower end of the float.

3. A supporting unit as set forth in claim 2, wherein the convex chamber is provided with an inwardly directed flange around its periphery perpendicular to the curved surface of the float, and a plurality of outwardly directed orifices formed in the flange and communicating with the outlet opening of the jetting pipe.

4. A submersible and retrievable supporting element for an off-shore drilling platform, comprising a rigid column having a vertically elongated float member rigidly secured at the lower portion thereof, said supporting element being equipped with conduit means extending downwardly along the length of the column for selectively supplying and removing fluent ballasting material to and from the float member to permit lowering or raising the same, and separate conduit means also extending through the float member for supplying under pressure jetting fluid beneath the float member to erode the soil from beneath said float and permit the same to settle deeply in the soil when the float member is being submerged or to facilitate removal of the float member from the soil when the float member is to be removed, said float member being of substantially greater length than its transverse dimension, permitting the float to be submerged within the subterranean soil by the action of the jetting fluid sufficiently to resist the wave and current action on the supports.

5. A supporting element for an off-shore drilling platform as defined in claim 4, wherein the float is provided with a longitudinally extending fin for increasing the area of contact with the subterranean soil after the float has been embedded therein.

KENNETH C. HOWARD.
